UNITED STATES PATENT OFFICE.

NICHOLAS JOSEPH PAULY, OF DUBUQUE, IOWA.

DESIGN FOR AN ENVELOP.

45,017.

Specification for Design.

Patented Dec. 9, 1913.

Application filed October 16, 1913. Serial No. 795,572. Term of patent 3½ years.

To all whom it may concern:

Be it known that I, NICHOLAS JOSEPH PAULY, a citizen of the United States, residing at Dubuque, in the county of Dubuque and State of Iowa, have invented a new, original, and ornamental Design for Envelops, of which the following is a specification, reference being had to the accompanying drawing, forming part thereof.

Figure 1 is a plan view of an envelop

showing my new design. Fig. 2 is an edge view.

I claim:

The ornamental design for an envelop as shown.

NICHOLAS JOSEPH PAULY.

Witnesses:

NICHOLAS J. LOES,
JOHN PAULY.
